UNITED STATES PATENT OFFICE

ADOLPH L. DE LEEUW, OF HAMILTON, OHIO.

SPEED-CONTROLLING SYSTEM.

No. 813,201.

Specification of Letters Patent.

Patented Feb. 20, 1906.

Application filed August 7, 1905. Serial No. 272,991.

To all whom it may concern:

Be it known that I, ADOLPH L. DE LEEUW, a citizen of the United States, residing in Hamilton, Butler county, Ohio, (post-office address, Hamilton, Ohio,) have invented certain new and useful Improvements in Speed-Controlling Systems, of which the following is a specification.

This invention, pertaining to speed - controlling systems, will be readily understood from the following description, taken in connection with the accompanying drawings, in which—

Figure 1 is a side elevation of an ordinary metal-planer having added thereto a speed-controlling mechanism exemplifying my invention; Fig. 2, a side elevation of the added mechanism in conjunction with certain of the ordinary parts of the planer; Fig. 3, an end elevation of the same, and Fig. 4 a diagram illustrating the typical electrical connections for the system.

In the drawings, 1 indicates the bed of an ordinary metal-planer; 2, the table; 3, the housings; 4, the planer-pulley of the cutting-belt; 5, the planer-pulley of the backing-belt; 6, the pulley-shaft of the planer; 7, the counter-shaft; 8, the cutting-pulley of the counter-shaft; 9, the backing-pulley of the counter-shaft; 10, the cutting-belt; 11, the backing-belt; 12, the electric motor; 13, the belt from the motor to the counter-shaft; 14, the starting-box of the motor; 15, the belt-shifter of the planer; 16, the reversing-tumbler; 17, the shifter-rod connecting the tumbler with the belt-shifter; 18, the cutting-dog or that one of the planer-dogs which, acting at the end of the backing motion, operates the tumbler and initiates the cutting stroke, and 19 the backing-dog.

All of the parts thus far referred to are as usual in metal-planers, and it may be further said that all these parts may be subject to any of the usual variations or modifications without materially affecting my automatic speed - controlling system, which may be viewed as supplemental to ordinary planer construction.

The parts thus far referred to operate in precisely the usual manner, and at this point it will be proper to consider the speed effects available in known constructions.

It will be observed that the proportioning of pulleys is such as to bring about the usual superior backing speed for the table, and the

proportioning of the backing speed to the cutting speed may be as usual and subject to the usual variations in design, dependent largely upon the size of the machine and the general character of the work to be done. As the backing motion is a non-productive one and represents a comparative waste of time, it is customary to provide for as high a backing speed as is practicable in view of the weight of the table and its work and the limitations to quick reversal of motion. The relation of backing speed to cutting speed having been fixed in the proportioning of the driving mechanism, that proportioning remains fixed, no matter what variations may be made in the cutting speed. In other words, assuming the backing speed to the cutting speed to be as four to one that proportioning holds good whether the cutting be done fast or slow, unless recourse be had to inconvenient change-gears or to independent motors for producing the cutting and the backing motion. The backing speed of a planer should be founded on considerations of weight of table and work regardless of whether the work be hard or soft, while the cutting speed should be founded on considerations of hardness or softness regardless of whether the work be light or heavy, for in ordinary planer operations it will be found that in most all cases the cutting speeds for tools are within any limiting conditions imposed by weight of parts to be moved or reversed.

By means of my system to be described I control the cutting speed and the backing speed quite independently of each other and without any necessary modifications of the speed proportioning arranged for in the design of the usual transmitting apparatus. While my system well lends itself to original incorporation into the mechanism of a planer designed with special reference to its employment, it also lends itself to constructions representing a mere supplement to the ordinary mechanism of the planer, and it is in this latter form that the system is illustrated in the exemplification.

Proceeding with the drawings, 20 indicates a rheostat of ordinary form for varying the speed of the motor and typifying motor-controlling devices generally; 21, the rheostat-arm; 22, the usual stop for the rheostat-arm, the arm being illustrated as in the maximum-speed position as reached by the movement

of the arm in clockwise direction from its minimum-speed position at the other side of the stop; 23, a pinion mounted on the planer-bed; 24, gearing connecting this pinion with the spindle of the rheostat; 25, a rack slidingly supported by the planer-bed and engaging the pinion; 26, a lug projecting to the front and the rear of the rack at the right of the reversing-tumbler; 27, a pawl carried by cutting-dog 18 in a plane to the rear of rack 25 and adapted as the cutting-dog moves to the left to engage lug 26 and push the rack to the left; 28, a pin projecting rearward from pawl 27; 29, a fixed cam in the path of pin 28 and adapted as dog 18 moves to the left to disengage pawl 27 from lug 26 and permit the rack to come to rest; 30, a second pawl carried by cutting-dog 18 in a plane to the front of rack 25 and adapted as the dog moves to the right to engage lug 26 and push the rack to the right; 31, a pin projecting forward from pawl 30, and 32 a cam to the right of lug 26 and in the path of pin 31 and adapted as the dog moves to the right and pushes the rack with it to release pawl 30 from lug 26.

In Fig. 2 assume the table to be moving in the direction of its arrow—that is to say—it is near the completion of its backing stroke, the reversing-tumbler 16 being in the position in which it was left by the backing-dog 19 at the beginning of the backing stroke. It is to be observed that arm 21 of the rheostat is in its highest-speed position, the consequence being that the motor is moving at maximum speed and the table backing at maximum speed.

The continued backing of the table eventually causes pawl 27 to engage lug 26, whereupon rack 25 moves to the left and the rheostat-arm moves progressively to slower motor positions, eventually reaching, say, the rheostat position corresponding with minimum motor speed. At this time pin 28 engages fixed cam 29, whereupon pawl 27 disengages from lug 26, the rheostat-arm then coming to rest at position corresponding with minimum motor speed. The table continues its backing motion, but has been slowed down to the minimum, and at this time dog 18 attacks the reversing-tumbler and reverses the table motion in the usual manner, this reversal obviously taking place under those favorable conditions represented by slow motor speed. The table motion having been reversed under these favorable slow conditions, the cutting stroke begins at the low speed. Soon after the reversal has taken place the pawl 30 engages lug 26 and moves rack 25 to the right, thus progressively readjusting the rheostat-arm again to high-speed position. At the time this is accomplished pin 31 engages cam 32, thus releasing pawl 30 from the rack and leaving the rheostat in high-speed condition, the table now proceeding on its cutting stroke at

high speed. For the present no attention need be given to any special performance on the part of the backing-dog 19. Cam 29 may be and is illustrated as a fixed cam, its duty being to disconnect the dog from the rheostat after the rheostat has been adjusted to minimum-speed position, the usual reversal of the planer motion taking effect after this slow-speed condition has been obtained. Cam 32 is illustrated as in a position to release the dog from the rheostat only after the rheostat has been adjusted to maximum-speed position. This represents the extreme of backing speed; but cam 32 is adjustable to the left, having screw-and-slot connection with its support. It is shown in its extreme rightward position. Its support is shown as being provided with five graduations. If now cam 32 be secured in some leftward position, it would manifestly cause dog 18 when it is connected to the rheostat and speeding up the motor to become disengaged from the rheostat when the rheostat-arm reaches some intermediate speed position. Under these conditions the cutting also, having been installed at minimum speed, continues at the speed corresponding with the adjustment of cam 32. It is therefore seen that by adjusting cam 32 the cutting speed may be as desired within the rheostat limits, the cutting motion of the table, however, always being initiated at low speed. In the illustration the rheostat is illustrated as having the usual great multiplicity of contact-points for the arm; but no such refinement of selection need be considered in adjusting cam 32.

The apparatus thus far described provides only for reversal at slow speed at the end of the backing stroke and for selective speeds for the cutting stroke after the cutting stroke has been initiated; but there is a second rack 33, engaging the pinion 23, and as complementary to this rack the backing-dog 19 is equipped with its pair of pawls, and there is a fixed cam for one pawl and an adjustable cam for the other pawl. The rheostat action is therefore the same at the end of the cutting stroke as has been described in connection with the backing stroke. The two adjustable cams being quite independent of each other permit the cutting-dog to adjust the rheostat for a cutting speed quite independent of the backing speed and permit the backing-dog to adjust the rheostat for backing speed quite independent of the cutting speed, each dog in its turn first slowing down the rheostat and then after the reversal of the planer has been effected at slow speed readjusting the rheostat for desired speed. By means of this system the planer may operate at any point within the rheostat conditions and may cut at high motor speed while backing at low motor speed or cut at low motor speed while backing at high motor speed.

thus accomplishing results not before attainable without the employment of change-gearing or a plurality of motors.

To those familiar with planing conditions it will be manifest that the highly-important results indicated can be arrived at under conditions involving a motor with a rather small range of speed variations. The diagram of electrical connections seen in Fig. 4 is typical merely. The starting-box 14 serves the usual purpose of gradually putting the current to the armature in starting up the motor, the motor being an ordinary continuously-running non-reversing one. The rheostat 20, controlled by the planer-dogs, varies the strength of the motor-field 34.

It is to be understood that the metal-planing machine is simply chosen as an exemplification of my improved speed-controlling system. This exemplification has been selected, as it presents peculiarly complicated and embarrassing conditions serving well to illustrate the capacity of my system, which it is obvious may well lend itself to quite a variety of machines capable of utilizing its merits to a greater or less degree.

I claim as my invention—

1. In a speed-controlling system, the combination, substantially as set forth, of a machine having a part to be moved at differing rates of speed, a continuously-running motor for driving the machine part, transmitting connections between the motor and the machine part, a controller for varying the speed of the motor, and connections between the controller and a moving part of the machine for causing the movement of said part to automatically adjust the controller and effect variations in the speed of the continuously-running motor.

2. The combination, substantially as set forth, with a machine provided with automatic reversing mechanism, a motor running continuously in one direction for actuating the machine, transmitting mechanism between the motor and the machine, a controller for varying the speed of the motor, and connections between the controller and a moving part of the machine, of means for causing said connections to effect an adjustment of the controller at each reversal of the machine, whereby the speed of the continuously-running motor and the machine may differ upon the forward and backing strokes of the planer.

3. The combination, substantially as set forth, with a machine provided with automatic reversing mechanism, a motor running continuously in one direction for actuating the machine, transmitting mechanism between the motor and the machine, a controller for varying the speed of the motor, and connections between the controller and a moving part of the machine, of means for causing said connections to adjust the controller in the motor-slowing direction before and in the motor-quickening direction after each reversal whereby the continuously-running motor causes the machine to reduce its rate of motion prior to and increase its rate of motion subsequent to each reversal.

4. The combination, substantially as set forth, with a machine provided with automatic reversing mechanism, a motor running continuously in one direction for actuating the machine, transmitting mechanism between the motor and the planer, arranged to cause a given speed of the motor to give to the machine a backing speed in excess of its forward speed, a controller for varying the speed of the motor, and connections between the controller and a part of the machine, of means for causing said connections to effect an adjustment of the controller at each reversal of the machine, whereby the speed of the continuously-running motor and the machine may differ upon the forward and backing strokes.

5. The combination, substantially as set forth, with a reciprocating machine provided with an automatic reversing mechanism, a motor running continuously in one direction for actuating the planer, transmitting mechanism between the motor and the planer, a controller for varying the speed of the motor, and mechanism connected with the controller for adjusting it, of means connected with said controller-adjusting mechanism and adapted to be engaged by dogs on a reciprocating part of the machine before and after each reversal of the motion of said part.

6. The combination, substantially as set forth, with a planing-machine provided with automatic reversing mechanism, a motor running continuously in one direction for actuating the planer, transmitting mechanism between the motor and the planer, a controller for varying the speed of the motor, and connections from the controller for adjusting it, of means whereby the planer-dogs engage with and disengage from said controller-adjusting mechanism prior to the reversal of table motion, and means for causing the planer-dogs to engage with and disengage from said controller-adjusting mechanism subsequent to the reversal of table motion.

7. The combination, substantially as set forth, with a planing-machine provided with automatic reversing mechanism, a motor running continuously in one direction for actuating the planer, transmitting mechanism between the motor and the planer, a controller for varying the speed of the motor, and connections from the controller for adjusting it, of means for causing the planer-dogs to engage with and disengage from said controller-adjusting mechanism prior to and again subsequent to the reversal of table motion, and means for variably adjusting the time of disengagement of the dogs from said controller.

ler-adjusting mechanism after the reversal of the table motion.

8. The combination, substantially as set forth, with a planing-machine provided with 5 automatic reversing mechanism, a motor running continuously in one direction for actuating the planer, transmitting mechanism between the motor and the planer, a controller for varying the speed of the motor, and connections from the controller for adjusting it, of means for causing the planer-dogs to engage with and disengage from said controller-adjusting mechanism prior to and again subsequent to the reversal of table motion, and 10 means for variably adjusting the time of disengagement of the dogs from said controller-adjusting mechanism after the reversal of the table motion, said variable adjusting means being independent as regards each dog, where- 15 by the release of each dog from the controller-adjusting mechanism after the reversal of table motion may occur under selected conditions independent of the corresponding adjustment for the other dog.
- 20 9. The combination, substantially as set forth, with a planing-machine provided with automatic reversing mechanism, a motor running continuously in one direction for actuating the planer, transmitting mechanism be- 25 tween the motor and the planer, a controller for varying the speed of the motor, and connections between the controller and a part of the planer moving in unison with its table, of means incorporated in said connections where- 30 by a planer-dog will adjust the controller to motor-slowng position, then effect the reversal of the table motion and then adjust the controller to motor-quickenng position.
- 35 10. The combination, substantially as set forth, with a planing-machine provided with automatic reversing mechanism, a motor running continuously in one direction for actuating the planer, transmitting mechanism be- 40 tween the motor and the planer, a controller for varying the speed of the motor, and con-

nctions from the controller for adjusting it, of means whereby the planer-dogs actuate the planer-reversing tumbler and the controller - adjusting mechanism at different times whereby the controller becomes adjust- 50 ed before and after the reversals of planer motion.

11. The combination, substantially as set forth, with a planing-machine provided with an automatic reversing mechanism, a motor 55 running continuously in one direction for actuating the planer, transmitting mechanism between the motor and the planer, a controller for varying the speed of the motor, and connections between the controller and a 60 part of the planer moving in unison with its table, of means for causing each planer-dog to adjust the controller to motor-slowng position and then to effect the reversal of table motion and then adjust the controller to mo- 65 tor-quickenng position.

12. The combination, substantially as set forth, with a planing-machine provided with an automatic reversing mechanism, a motor running continuously in one direction for 70 actuating the planer, transmitting mechanism between the motor and the planer, a controller for varying the speed of the motor, and connections between the controller and a 75 part of the planer moving in unison with its table, of means for causing said connections to slow the table motion before reversal thereof and to quicken the table motion after the reversal thereof, and means independent for each dog for adjusting selectively the degree 80 of said quickening whereby the continuously-running motor moves the table at speed decreased before reversal and at speed increased after reversal and whereby the table speeds after reversal may be selectively different for 85 the cutting and the backing stroke.
